ATTORNEY

UNITED STATES PATENT OFFICE

JOSEPH J. KISPERT, OF BRADFORD, CONNECTICUT, ASSIGNOR TO I. NEWMAN & SONS, INC., OF NEW HAVEN, CONNECTICUT, A CORPORATION OF CONNECTICUT

CORSET

Application filed December 27, 1927. Serial No. 242,774.

This invention relates to corsets, and particularly to what is commonly known as a wrap-around corset, the object being to provide a form of corset which is of substantially 5 a conventional type, but with improved means at the front for taking up stretching of the various parts of the corset.

Another object of the invention is to provide a corset with a normally permanently 10 positioned section at the front and a plurality of series of fastening means associated with the front section and the remaining part of the corset adjacent the front section so that the normally permanent front section 15 may be removed when desired.

A further object, more specifically, is to provide a wrap-around corset having elastic sections, and a removable though normally permanent section at the front and an auxiliary series of fastening means adjacent the permanent section.

In the accompanying drawing—

Figure 1 is a perspective view of a corset disclosing an embodiment of the invention, the same being shown on a figure.

Figure 2 is an enlarged fragmentary front view of part of the corset shown in Figure 1, the same illustrating the normally permanently secured front section.

Figure 3 is a section through Figure 2 on line 3—3, the same being on an enlarged scale.

Figure 4 is a sectional view through Figure 2, approximately on line 4—4, the same being on an enlarged scale.

Referring to the accompanying drawing by numerals, 1 indicates a corset body as a whole, which is provided at one or both sides with an elastic section 2 extending preferably from the top to the bottom of the corset. Connected to the front edges of the sections 2 are front flaps or sections 3 and 4. Section 3 is provided with the usual fastening loops 5, while section 4 is provided with an auxiliary normally permanently secured section 6. The auxiliary section 6 is provided with a row of fastening studs 7 co-acting with the loops 5 to hold the corset in position as shown in Figure 1 when the corset is new. After the corset has been used

for a while, sections 2 will stretch to a greater or less extent, and also the other parts of the corset will stretch slightly. As the corset is a wrap-around corset, there is no means for taking up this stretch ordinarily. In the present instance, however, section 6 is removed, and the fastening loops 5 caused to fit over the various studs 8 on section 4. The normally permanent section 6 is formed with a piece of fabric 9 bent upon itself as shown in Figure 3 and enclosing the member 10 which carries the ends of studs 7.

Any suitable form of structure could be used, provided the fabric 9 extended over to the section 4 where it is secured by lines of stitching 11, 12 and 13 as shown in Figure 3. As shown in Figure 3, the fabric 9 is bent back upon itself at 14 and held in place by stitches 15. The bent back section 14 is spaced a short distance from the bent back section 16 of the fabric 17 forming the principal part of section 4. The lines of stitching 12 and 13 enclose the fabric 18 forming a pocket for the stay or metal strip 19 carrying the studs 8.

As shown in Figure 2, in addition to the studs 7 and 8, there are provided metal or other loops 20 and 21 which co-act with suitable hooks 22 on section 3. A guiding line of stitching 23 is placed in fabric 9 between the sections 4 and 6. This line of stitching is intended to act as a guiding line whereby the fabric 9 may be cut approximately at the point indicated by the dot-and-dash line 24. When the fabric 17 is cut substantially along this line, there is a slight ragged edge on this fabric, but by reason of the bent back portion 16, a smooth edge is presented to the eye and a new row of studs 8 is in position to co-act with the fasteners 5. At the top and bottom, suitable ornamental braids 25 and 26 are provided. As indicated in Figure 4, the braid 25 is adapted to be cut at the point 27, but by reason of the stitches 28, a comparatively smooth edge is presented, or at least a binding set of threads persentated which will prevent unnecessary ravelling.

When the corset is new, it is naturally designed to properly fit as shown in Figure 1. A person selecting a corset, will naturally

select one that will fit snugly and give the desired appearance when the fasteners 5 are engaged with the studs 7. In the course of time, the corset will permanently stretch, and particularly the elastic sections 2. As there are no lacings or other take up means for a wrap-around corset, the corset becomes loose and, therefore, does not function properly. Heretofore, when this took place, it was necessary to either throw the corset away or to place new elastic sections 2 in the corset body. In the present instance, however, this is not necessary, as when the corset stretches permanently, the section 6 may be removed by cutting the same away from section 4. This will leave the loops 21 exposed and cause the studs 8 to be in position to be engaged by the loop fastening members 5, while hooks 22 may engage the loops 21. The removing of the section 6 may be done by anyone, as it is merely necessary to cut along the line of stitching 23 with a pair of scissors and in cutting, the braids 25 and 26 will be cut as described. The binding thread 28 at the top and bottom presents a finished edge at these points, and the bent back portion or section 16 presents a finished edge between the top and bottom braids so that after the section 6 has been removed, the corset will have substantially the usual appearance and yet will be restricted in size.

What I claim is:

1. A wrap-around corset, formed with a body open at the front, an independent section normally permanently secured to one edge of the front of the corset so as to act as a continuation thereof, means on said independent section presenting a cutting line which is independent of said body, whereby when said body has been stretched, said independent section may be removed without injuring said body by cutting along said cutting line, a row of fastening means on the front edge of the corset, a second row of fastening means on the edge of said continuation, said second row being parallel to the first row, and a row of co-acting fastening means on the opposite edge of the corset, said last mentioned fastening means co-acting with the row of fastening means on the continuation when the corset is new and with the first mentioned row of fastening means when said independent section has been removed.
2. A wrap-around corset, comprising in combination a body open at the front, a row of fastening means on one front edge of said body and a pair of coacting parallel rows of fastening means on the other front edge of said body, said other front edge comprising a pair of fastener holding sections, one section having the outer part bent back upon itself for forming an unravelling edge and the other section having a part extending past said unravelling edge and completely

underlapping the first-mentioned section, lines of stitching connecting said extending part to the first-mentioned section, one of said lines of stitching extending through said unravelling edge, whereby said extending part may be cut along said unravelling edge to remove the second-mentioned section without injuring the remaining part of the corset.

Signed at New York, in the county of New York and State of New York, this 23rd day of December, A. D. 1927.

JOSEPH J. KISPERT.
